PISTON ROD PROTECTOR

Theodore Kenneth Helmer, Fellows, Calif.

Application April 17, 1936, Serial No. 74,938

10 Claims. (Cl. 103—202)

This invention relates generally to protectors for pumps and the like, and specifically contemplates a collapsible cylindrical enclosure for the rod of a reciprocating-piston type pump, thereby to separate the bearing and packing element from abrasive substances in the fluid to be pumped.

While the device of my invention as herein-after described may be made adaptable for use in a wide variety of types of pumps, the accompanying disclosure will be directed to an embodiment thereof particularly applicable to slush pumps commonly employed in well drilling.

As is well known, the mud fluid circulated 15 through the bore of deep wells drilled by rotary methods is composed of materials to form a consistency of sufficient weight to maintain in suspension drill cuttings and cavings, until they may be raised in the fluid to the surface of the well for deposition in a settling ditch. Materials economically available for such fluid necessarily include 20 abrasive particles which must pass through the pump for circulation in the well. Furthermore, the density of the mud precludes the entire removal of the detrital material taken from the well or even the substantial cleansing of the fluid, except by excessively expensive methods, before 25 it must again be returned to the well bore by the slush pump.

The extremely high pressure often utilized in such pumps of the well drilling art tends to force these abrasive particles carried by the fluid motivated, as well as the original attrite constituents of the mud, into the bearings and packing of the 30 piston rod, which results in excessive wear with a consequent loss in efficiency and necessitates frequent replacement of the parts.

It is a principal object of the present invention to provide a protector for the piston rod of reciprocating pumps whereby a separate chamber is formed within the pump cylinder for the reciprocation of the rod which isolates the bearings and packing elements with respect to the working chamber of the pump to prevent contamination 40 thereof by abrasive materials carried in the fluid motivated by the pump.

Another object is to provide a flexible cylinder forming a sealed collapsible chamber between the piston and cylinder end wall of the working chamber of a reciprocating pump in which the piston rod is adapted to operate, embodying means actuated by the working pressure of the pump to correspondingly vary the pressure within 45 the sealed chamber and thereby obviate the

formation of a pressure differential between the zones within and around the flexible cylinder.

Another object is the provision of a device easily applied to oil well slush pumps as at present designed for the art, which is simple in construction, facilitating replacement of worn parts, economical in manufacture and efficient in operation.

Other objects will be apparent to those of skill in the art to which the present invention appertains upon an examination of the following description read in the light of the accompanying drawing, in which—

Fig. 1 is a sectional view of my invention as applied to the piston and rod of a double acting slush pump;

Fig. 2 is an enlarged fragmentary sectional view of the attachment of the flexible cylinder to the end wall of the working chamber of the pump;

Fig. 3 is a sectional view similar to Fig. 2 illustrating the attachment of the flexible cylinder to the piston;

Fig. 4 is a sectional view of a modified form of pressure tank.

Referring to the drawing in detail, the numerals of which indicate similar parts throughout the several views, 5 designates generally the portions of the body of a slush pump which are adjacent the working chamber 6 of the pump. The details of the pump, which may be of any type well known in the art, are not illustrated or further described. A steel liner 7 is provided in the body 5, in which a piston 8, later referred to, is adapted to reciprocate.

Through a bearing 9 in the end wall 10 of chamber 6 of the body of the pump and concentrically into the liner 7 a piston rod 11 extends. The various drive mechanism for the reciprocation of the piston rods are likewise familiar to the art, and forming no part of the present invention, are not set forth.

Integral with the outside of the end wall 10, a stuffing box 12 encircles rod 11 in which packing 13 is compressed by a gland 14 in a well known manner. Near the end of rod 11 within liner 7, the diameter of the rod is increased to form a beveled shoulder 15. A concavo-convex washer 16 having its concave surface corresponding to the bevel of shoulder 15 is arranged on rod 11 adjacent the shoulder against which a similarly shaped concavity 17 of piston head 18 is adapted to seat. A nut 19 threaded on the end of rod 11 clamps the piston 8 and washer 16 rigidly against the shoulder 15.

An annular rim 20 of washer 16, projecting

from between piston head 18 and shoulder 15 of the rod is turned inwardly, substantially parallel with the rod. One end of a cylinder 21, composed preferably of rubber or other flexible impervious material, encircles rim 20 and is secured in a groove 22 formed on the periphery of the rim by means of a hose clamp 23 to provide a fluid-tight connection.

The opposite end of the cylinder 21 is similarly attached by hose clamp 24 on the periphery of a collar 25 which encircles rod 11. Collar 25 is threaded on a hub 26 which is welded or otherwise secured to the end wall 10 around rod 11. Studs 27 are radially mounted on collar 25 to facilitate attachment and removal thereof relative to the hub.

From the above description it will be apparent that fluid drawn into the working chamber 6 of the pump, and which is compressed on the opposite stroke of the piston, will not contact rod 11 or end wall 10 adjacent bearing 8 at any time during operation of the pump.

To prevent fracture of the cylinder 21 as the piston is moved on its pumping stroke, pressure within the flexible cylinder is maintained substantially equal to that outside thereof by communication of the space within and around the cylinder with a variable pressure tank 28 about to be described. Tank 28 is preferably constructed in two sections 29 and 30, between the abutting edges of which a flexible membrane 31 is secured to divide the tank into chambers 32 and 33. A tube 34 extending from chamber 33 is connected with a passage 35 through end wall 10 which opens 35 into the bore of hub 26 around the rod, thus communicating the space within the cylinder 21 with chamber 33 of the tank. Chamber 33 and the cylinder 21 are filled with a fluid of substantially the same density and compressibility as the fluid 40 passing through the pump. Another tube 36 connects, through a hole 37 in the wall of section 29 of tank 28, the working chamber 26 with chamber 32 of the tank.

It will thus be seen that pressure in the cylinder 21 and chamber 33 will be maintained equal to the pressure within working chamber 6 and chamber 32 by the resiliency of membrane 31. Any tendency toward a pressure differential during operation of the pump between the spaces 50 within and around the cylinder 21 coincidentally influences pressure within their respectively-connected chambers 33 and 32 of tank 28. Membrane 31 will accordingly obviate the creation of a pressure differential between the spaces within 55 and around the flexible cylinder, which might result in distortion or fracture of the cylinder, by expanding into the chamber of the lowest pressure.

A container 38 for additional fluid for chamber 60 33, to compensate for loss by leakage, or to facilitate filling or draining of the tank during replacement of the membrane or flexible cylinder 21, is connected by a pipe line 39 extending through section 30 into chamber 33 of the tank. A hand pump 40 of a type well known in the art is disposed in pipe line 39 to impel fluid from the container 38 to chamber 33. A pressure gauge 41 of a well known type is located in pipe line 39 to enable accurate measurement of the 65 injection of the fluid into tank 28. After assembly of the pump, and my invention therewith, a valve 42, provided in the wall of section 29, should remain open during the first stroke of the piston 70 to compel pressure fluid from the working chamber 75

to expel air or other highly compressible gas trapped therein.

A modified form of pressure tank is illustrated in Fig. 4, comprising a cylinder 43 in which an annular piston 44, having an opening 45 therein, is adapted to move. A flexible membrane 46 is attached to the piston over opening 45, by well known means, to divide the cylinder into chambers 47 and 48 at opposite sides of the piston. The ends of the cylinder are communicated with the pump in the manner above described in detail, by means of nipples 49 threaded into holes 50 in the cylinder. Abutments 51 are secured in the cylinder bore adjacent each nipple 49 to limit the stroke of the piston to the zone between holes 50, thereby enabling the slightest differential in pressure between the chambers at opposite sides of the piston to move the piston and membrane for the purpose above indicated in the description of the embodiment illustrated in Fig. 1.

It should be understood that numerous changes may be made in the embodiments shown as to size, proportion, relative arrangement and design of the various parts; that a solid piston may 25 be substituted for the annular piston illustrated in Fig. 4 or the membrane shown in Fig. 1; and that other means well known in the art may be employed for releasably attaching the flexible cylinder to the piston and end wall of the working 30 chamber of the pump, without departing from the spirit of my invention as defined in the appended claims.

What I claim and desire to secure by Letters Patent is:

1. In a pump having a cylinder in which a piston is reciprocated by means of a piston rod, a flexible enclosure around the piston rod between the piston and end wall of the cylinder, means to seal the zone within the enclosure with respect 40 to the area around the enclosure, and means to regulate pressure within the enclosure by pressure around the enclosure.

2. In a pump having a cylinder in which a piston is reciprocated by a piston rod, a collapsible enclosure encircling the rod between the end wall of the pump cylinder and the piston, means to connect the ends of said enclosure to, respectively, the piston head and end wall of the pump cylinder, thereby separating the piston rod from 50 the effective working area of the pump, and means to maintain equal pressure within and around the enclosure.

3. In a reciprocating piston type pump, a collapsible enclosure encircling the piston rod having one end connected to the end wall of the pump cylinder and its other end connected to the piston, a container, a wall dividing said container into two chambers, said wall being movable to vary the size of the chambers upon the creation of a pressure differential between the chambers, and communicating means from opposite chambers to, respectively, the zones within and around the collapsible enclosure.

4. In a reciprocating piston type pump, a collapsible enclosure to separate the portion of the piston rod which contacts the end wall bearing of the rod from the effective working area of the pump, a container, means to communicate pressures created in, respectively, the zones within and around said enclosure by reciprocation of the piston to opposite ends of said container, and a movable wall dividing the container into two chambers adapted to reduce the size of one of said chambers by increased pressure in the other. 75

5. In a pump, a cylinder, an end wall for said cylinder, a piston within said cylinder, a piston rod connected with said piston and journaled in a bearing in said end wall, enclosure means to enclose the portion of the rod contacting the bearing with the portion of the end wall adjacent said bearing to thereby isolate the bearing with respect to the effective pumping area of the cylinder, and means to equalize pressure within and around the enclosure means.

6. In a pump, a cylinder having an end wall, a piston in said cylinder, a piston rod journaled in said end wall having a bevelled annular shoulder, a bevel-faced washer of a width greater than the width of said shoulder and adapted to seat on said shoulder, the said piston adapted to seat on said washer, a collapsible enclosure encircling said rod having one end secured to said washer, means to maintain a fluid tight fit between said washer and enclosure, and means to removably secure the opposite end of said enclosure to said end wall.

7. In a pump, a cylinder having an end wall, a piston in said cylinder, a piston rod journaled in said end wall carrying a bevelled annular shoulder, a bevel-faced washer of a width greater than the width of said shoulder and adapted to seat on said shoulder, a piston adapted to seat on said washer, a collapsible enclosure encircling said rod having one end secured to said washer, means to maintain a fluid tight fit between said washer and enclosure, means to removably secure the opposite end of said enclosure to said end wall, and means to regulate

pressure within said enclosure by pressure created around said enclosure.

8. In a device of the character described, a pump cylinder, a piston rod extending into said cylinder carrying a bevelled annular shoulder, a washer having its opposed annular faces parallel to said shoulder, said washer having an annular flange at its edge, a cylindrical flexible enclosure encircling the piston rod having one end sealed to said flange, means to connect the other end of said enclosure to the end wall of the cylinder around the piston rod, and a piston having a conical convexity concentrically formed therein adapted to seat on said washer.

9. In a pump, a body having a pump chamber therein, a bearing in said body, a rod extending through said bearing, a piston within said pump chamber connected to said rod, a flexible inclosure around the portion of said rod adapted to contact said bearing, means to seal the opposite ends of said inclosure with the rod and body, respectively, and means to regulate pressure within the inclosure by pressure around the inclosure.

10. In a pump, a body having a pump chamber therein, a bearing in said body, a rod extending through said bearing, a piston within said pump chamber connected to said rod, a flexible inclosure around the portion of said rod adapted to contact said bearing, means to seal the opposite ends of said inclosure with the rod and body, respectively, and means to maintain pressure within the inclosure substantially equal to the pressure around the inclosure.
